UNITED STATES PATENT OFFICE.

JOHN F. WHITE, OF PITTSBURGH, PENNSYLVANIA.

DESIGN FOR A NUTCRACKER.

49,200.

Specification for Design. Patented June 13, 1916.

Application filed April 6, 1916. Serial No. 89,503. Term of patent 7 years.

To all whom it may concern:

Be it known that I, JOHN F. WHITE, a citizen of the United States, residing at Pittsburgh, in the county of Allegheny and State of Pennsylvania, have invented a new, original, and ornamental Design for a Nutcracker, of which the following is a specification, reference being had to the accompanying drawing, forming part thereof.

The figure is a perspective view of a nut cracker, showing my new design.

I claim:

The ornamental design for a nutcracker, as shown.

JOHN F. WHITE.
